UNITED STATES PATENT OFFICE.

JOHN S. BOND, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

CRUSHER AND METHOD OF CONSTRUCTING THE SAME.

Application filed June 12, 1924. Serial No. 719,513.

This invention relates in general to improvements in the art of manufacturing machine elements which are subject to destructive shrinkage strains, and relates more specifically to improvements in crusher structures and to an improved method of constructing certain elements of such structures.

An object of the invention is to provide a crusher which is simple in construction and efficient in operation. Another object of the invention is to provide an improved method of constructing crusher structures.

In the manufacture of certain types of machines such as gyratory crushers, it is desirable to provide a one-piece element comprising an outer shell and a bearing located centrally therein, the shell and bearing being formed of a single casting and being rigidly connected by means of one or more radial ribs. The connecting ribs of such elements of some gyratory crushers, have heretofore been cast solid and integral with both the shell and the bearing. Due to shrinkage stresses in the ribs produced during casting of the structure, these ribs would frequently break thus necessitating repairing of the ribs in order to permit them to function as struts for the purpose of maintaining the bearing in proper position during normal operation of the crusher. In an endeavor to avoid such breakage of the ribs due to shrinkage stresses, it was proposed to cast the ribs solid and to subsequently cut and drill through the ribs, thereby dividing them into sections and relieving them of stresses which might tend to cause breakage. After the ribs were thus divided and the stresses eliminated, it was proposed to insert filler pieces at the divisions in order to reconvert the ribs into struts for preventing displacement of the center bearing. Such proposed structure forms the subject of U. S. Letters Patent No. 1,607,649, granted November 23, 1926, and while it eliminated breakage of the connecting ribs, the proposed method of eliminating the stresses in the ribs was faulty in that unequal stresses in the ribs would cause the bearing to shift out of desired position when the cutting and drilling of the ribs was effected.

The present invention contemplates provision of such a crusher structure and of a method of producing the same, whereby un-

desirable shrinkage stresses are positively avoided during formation of the casting, thus eliminating possible displacement of the bearing relatively to the shell at all times. In accordance with the improvement, the ribs are cast in sections separated by a core during the casting operation. The spaces formed by these cores are subsequently closed by means of filler pieces to convert the divided ribs into struts capable of permanently effectively maintaining the bearing in proper position within the shell.

A clear conception of an embodiment of the invention and of the steps of the method of producing structures embodying the same, may be had by referring to the drawing accompanying and forming a part of this specification in which like reference characters designate the same or similar parts in the various views.

Fig. 1 is a side elevation of a gyratory crusher, the lower portion thereof being shown in section.

Fig. 2 is an enlarged horizontal section through the gyratory crusher, the section being taken along the line II—II of Fig. 1.

Fig. 3 is an enlarged fragmentary horizontal section through the bearing member and one of the retaining ribs of the gyratory crusher structure.

Fig. 4 is an enlarged fragmentary side elevation, partly in section, of the central bearing element and one of the retaining ribs of the gyratory crusher structure.

While the invention is disclosed herein as being specifically applied to a gyratory crusher structure, it will be obvious that the principles are capable of more general application. The gyratory crusher specifically illustrated comprises in general a lower support consisting of an outer shell member 14 and an inner bearing member 15 mounted centrally therein; an upper annular shell or concave section 9 fixedly mounted upon the lower support and having the usual spider mounted thereon; a frusto conical crushing head 8 located within the concave section 9; a main crusher shaft 7 upon which the crushing head 8 is mounted and having a lower extremity extending within the bearing member 15; a rotary eccentric 16 embracing the lower extremity of the main shaft 7 and rotatable within the bearing member 15; a pulley 20 and countershaft 19

rotatably supported within the lower portion of the supporting element; and a bevel gear 17 and pinion 18 for communicating rotary motion from the countershaft 19 to the eccentric 16 in a well known manner.

The lower supporting element consisting of the outer shell member 14 and the bearing member 15 is provided with a diaphragm 13 extending at an incline from the top to the bottom of the supporting element and connecting the members 14, 15. In addition to the diaphragm 13, the members 14, 15 are preferably connected by a series of ribs 10, 11, 12 extending substantially radially with respect to the bearing member 15 and comprising sections 22, 23 formed integral with the members 14, 15 respectively. It will be noted that the diaphragm 13 is also formed integral with the members 14, 15 and that the entire supporting element comprising the shell member 14, bearing member 15, diaphragm 13, and ribs 10, 11, 12 is cast en bloc.

During the formation of the lower crusher element by casting, the spaces 21 between the rib sections 22, 23 are provided with cores which positively separate the ribs 10, 11, 12 into sections 22, 23, these rib sections being free to expand and contract during cooling of the casting and thus eliminating shrinkage strains between the bearing member 15 and the shell member 14 through the ribs. After the rough casting has been formed, the surfaces bounding the spaces 21 are finished to permit insertion of the pins 2, 3. The pins 2 which are utilized to complete the upper ribs 10, 11 are preferably tapered downwardly as shown and are held in firm engagement with the rib sections 22, 23 by means of nuts 4 coacting with the lower extremities thereof. The pin 3 which is utilized to complete the lower rib 12 may be either straight or tapered upwardly as shown. Due to the fact that the ribs 10, 11 are located in the direct path of material passing through the crusher, these ribs may be provided with liner plates 5 coacting with lugs 6 as shown.

It has been found that by casting the ribs 10, 11, 12 in sections, elimination of all undesirable shrinkage stresses is positively eliminated and the bearing member 15 may readily be maintained in proper position

within the shell member 14 at all times. While only three ribs have been illustrated in the drawing, it will be obvious that any number of these ribs may be utilized and that the spaces 21 may be formed either at or intermediate the ends of the ribs 10, 11, 12. It is moreover not necessary to utilize tapered circular pins as shown, for the purpose of subsequently uniting the rib sections, and it is obvious that any other connecting means may be employed. The filler pieces or pins 2, 3 serve to convert the ribs into struts which permit transmission therethrough of lateral thrust induced during crushing upon the lower end of the main shaft 7.

It should be understood that it is not desired to limit the invention to the exact details of construction herein shown and described, for various modifications within the scope of the claims may occur to persons skilled in the art.

It is claimed and desired to secure by Letters Patent:

1. The method of constructing a crusher frame consisting of an outer shell member and a bearing member located therein, which comprises, casting at least one of said members with a rib section extending toward but disconnected from the other member, and subsequently completing the connection between said rib section and said other member.

2. The method of constructing a crusher frame consisting of an outer shell member and a bearing member located therein, which comprises, casting both of said members with integral disconnected rib sections extending toward each other, and subsequently uniting said rib sections to form a strut.

3. The method of constructing a crusher frame consisting of an outer shell member and a bearing member located therein, which comprises, casting said members en bloc with integral disconnected rib sections extending from the one toward the other at spaced portions of said members, and subsequently completing the connection between said members through said sections.

In testimony whereof, the signature of the inventor is affixed hereto.

JOHN S. BOND.
